(57) **ABSTRACT**

An integrated circuit includes a current mirror configured to provide a first current to a first node, provide a second current to a second node virtually shorted to the first node, and provide a third current to a voltage output node. The integrated circuit further includes a first pn junction element between the first node and a ground line, a first resistor element between the second node and the ground line, a second pn junction element coupled in series to the first resistor element, a first load component configured to generate an output voltage at the voltage output node, and a subsequent stage circuit configured to generate an output signal based on the output voltage. The first load component is configured to cause the output voltage to have a non-zero temperature dependence that at least partially cancels a temperature dependence of the output signal of the subsequent stage circuit.

TEMPERATURE COMPENSATION FOR
INTEGRATED CIRCUITS

TECHNICAL FIELD

This disclosure relates generally to integrated circuits and more particularly to temperature compensation for integrated circuits.

BACKGROUND

Integrated circuits are often desired to generate a temperature-stabilized output signal. For example, a constant current source may be desired to generate a current that is constant with temperature, and an oscillator circuit may be desired to generate an oscillating output of a frequency that is constant with temperature.

One method for generating a temperature-stabilized output signal is to use a bandgap voltage reference (BGR) circuit. To improve the temperature stability, an integrated circuit may incorporate a BGR circuit and generate an output signal using a temperature independent voltage generated by the BGR circuit. For example, a constant current source may be configured to generate a constant current by performing a voltage-to-current conversion on a temperature independent reference voltage generated by a BGR circuit.

SUMMARY

This summary is provided to introduce a selection of concepts, in a simplified form, that are further described below. This summary is not necessarily intended to identify key features or essential features of the present disclosure. The present disclosure may include the following various aspects and embodiments.

In an exemplary embodiment, the present disclosure provides an integrated circuit. The integrated circuit includes a first current mirror, a first pn junction element, a first resistor element, a second pn junction element, a first load component, and a subsequent stage circuit. The first current mirror is configured to provide a first current to a first node, provide a second current to a second node virtually shorted to the first node, and provide a third current to a first voltage output node. The first pn junction element is coupled between the first node and a ground line. The first resistor element is coupled between the second node and the ground line. The second pn junction element is coupled in series to the first resistor element. The first load component is coupled between the first voltage output node and the ground line and configured to generate a first output voltage at first voltage output node. The subsequent stage circuit is configured to generate an output signal based on the first output voltage. The first load component is configured to cause the first output voltage to have a non-zero temperature dependence that at least partially cancels a temperature dependence of the output signal of the subsequent stage circuit.

In another exemplary embodiment, the present disclosure provides a method. The method includes providing, by a first current mirror, a first current to a first node coupled to a ground line via a first pn junction element. The method further includes providing, by the first current mirror, a second current to a second node virtually shorted to the first node. The second node is coupled to the ground line via a second pn junction element and a first resistor element coupled in series. The method further includes providing, by the first current mirror, a third current to a first voltage

output node. The method further includes generating, by a first load component coupled between the first voltage output node and the ground line, a first output voltage at the first voltage output node. The method further includes generating, by a subsequent stage circuit, an output signal based on the first output voltage. The first output voltage has a non-zero temperature dependence that at least partially cancels a temperature dependence of the output signal of the subsequent stage circuit.

10 Other features and aspects are further described below with reference to the attached drawings.

BRIEF DESCRIPTION OF THE DRAWINGS

15 FIG. 1 shows an example configuration of an integrated circuit, according to one or more embodiments.

FIG. 2 shows another example configuration of an integrated circuit, according to one or more embodiments.

20 FIG. 3 shows an example configuration of a subsequent stage circuit, according to one or more embodiments.

FIG. 4 shows yet another example configuration of an integrated circuit, according to one or more embodiments.

FIG. 5 shows an example configuration of a variable resistor element, according to one or more embodiments.

25 FIG. 6 shows yet another example configuration of an integrated circuit, according to one or more embodiments.

FIG. 7 shows yet another example configuration of an integrated circuit, according to one or more embodiments.

30 FIG. 8 is a flowchart of an exemplary process for operating an integrated circuit, according to one or more embodiments.

FIG. 9 is a block diagram of an exemplary integrated circuit.

To facilitate understanding, identical reference numerals have been used, where possible, to designate elements that are common to the figures. It is contemplated that elements 35 disclosed in one embodiment may be utilized in other embodiments without specific recitation. Suffixes may be attached to reference numerals to distinguish elements from each other. The drawings referenced to herein are not to be construed as being drawn to scale unless specifically noted.

40 In addition, the drawings are often simplified and details or components are omitted for clarity of presentation and explanation. The drawings and discussion serve to explain principles discussed below.

DETAILED DESCRIPTION

The following detailed description is exemplary in nature and is not intended to limit the disclosure or the applications and uses of the disclosure. Furthermore, there is no intention 50 to be bound by any expressed or implied theory presented in the preceding background, summary and brief description of the drawings, or in the following detailed description.

In the following detailed description, numerous specific details are set forth in order to provide a more thorough understanding of the disclosed technology. However, it will be apparent to one of ordinary skill in the art that the disclosed technology may be practiced without these specific details. In other instances, well-known features have not been described in detail to avoid unnecessarily complicating the description.

The term "coupled" as used herein means connected directly to or connected through one or more intervening components or circuits. Further, throughout the application, ordinal numbers (e.g., first, second, third, etc.) may be used 65 as an adjective for an element (i.e., any noun in the application). The use of ordinal numbers is not to imply or create any particular ordering of the elements nor to limit any

element to being only a single element unless expressly disclosed, such as by the use of the terms “before”, “after”, “single”, and other such terminology. Rather, the use of ordinal numbers is to distinguish between the elements. By way of an example, a first element is distinct from a second element, and the first element may encompass more than one element and succeed (or precede) the second element in an ordering of elements.

One method of generating a temperature-stabilized output signal is to use a bandgap voltage reference (BGR) circuit, which can generate a temperature independent reference voltage based on the temperature characteristics of pn junction elements, such as diodes and bipolar transistors. An integrated circuit may be configured to generate a temperature independent reference voltage by a BGR circuit and to generate a temperature-stabilized output signal from the temperature independent reference voltage by a subsequent stage circuit.

This method may not however sufficiently suppress the temperature dependence of the output signal if the subsequent stage circuit exhibits a significant temperature dependence. For example, in implementations where the subsequent stage circuit is configured as a voltage-to-current conversion circuit that uses a voltage-to-current conversion resistor, the resulting current may exhibit a significant temperature dependence due to the temperature characteristics of the voltage-to-current conversion resistor. Accordingly, there is a technological need to provide a novel technology for generating a temperature-independent signal.

The present disclosure recognizes that the temperature dependence of the output voltage of a BGR circuit is flexibly adjustable with circuit element parameters, such as resistor resistances and transistor sizes. The present disclosure takes advantage of the flexibility in adjusting the temperature dependence of the output voltage of a BGR circuit to enable an integrated circuit to generate a temperature-stabilized output signal. In one or more embodiments, an integrated circuit includes a BGR-based voltage generator circuit and a subsequent stage circuit. The BGR-based voltage generator circuit is configured to generate an output voltage having a non-zero temperature dependence, and the subsequent stage circuit (e.g., a voltage-to-current conversion circuit) is configured to generate a desired output signal (e.g., a temperature-independent constant current, an oscillating output of a temperature-independent frequency etc.) using the output voltage of the BGR-based voltage generator circuit. The non-zero temperature dependence of the output voltage of the BGR-based voltage generator circuit is adjusted to at least partially cancel the temperature characteristics of the subsequent stage circuit. This effectively achieves improved temperature compensation, allowing the subsequent stage circuit to generate an output signal that is stable with temperature. Described below are various embodiments of the present disclosure which achieve improved temperature compensation based on a BGR-based voltage generator circuit.

FIG. 1 shows an example configuration of an integrated circuit **1000**, according to one or more embodiments. In the shown embodiment, the integrated circuit **1000** includes a voltage generator circuit **100** and a voltage-to-current conversion circuit **200**. The voltage generator circuit **100** is configured to generate and provide a first output voltage V_{O1} and a second output voltage V_{O2} based on a BGR-based circuit configuration. The voltage-to-current conversion circuit **200** is a subsequent stage circuit configured to perform a voltage-to-current conversion on the first output voltage V_{O1} to generate a constant output current I_{const} . As dis-

cussed in detail later, the first output voltage V_{O1} is generated to have a non-zero temperature dependence that at least partially cancels the temperature dependence of the constant output current I_{const} , while the second output voltage V_{O2} is generated to be substantially constant with temperature. The voltage generator circuit **100** includes a first current mirror **110**, a first operational amplifier **120**, a second current mirror **130**, a second operational amplifier **140**, a first load component **150**, a second load component **160**, a resistor element **180**, and bipolar transistors **Q1**, **Q2**, and **Q3**.

The first current mirror **110** is coupled to a power supply line **170** that provides a high-side power supply voltage V_{DD} and is configured to generate first, second, third, fourth, and fifth currents I_1 , I_2 , I_3 , I_4 , and I_5 such that the currents I_1 , I_2 , I_3 , I_4 , and I_5 have the same current level. In the shown embodiment, the first current mirror **110** includes p-channel metal oxide semiconductor (PMOS) transistors **MP1**, **MP2**, **MP3**, **MP4**, and **MP5** that have commonly-coupled gates. The sources of the PMOS transistors **MP1** to **MP5** are commonly coupled to the power supply line **170**. The PMOS transistors **MP1**, **MP2**, and **MP3** have drains coupled to nodes N_1 , N_2 , and N_3 , respectively, and are configured to provide the first, second, and third currents I_1 , I_2 , and I_3 , respectively, to the nodes N_1 , N_2 , and N_3 . The PMOS transistors **MP4** and **MP5** have drains coupled to the first and second voltage output nodes $N_{V_{O1}}$ and $N_{V_{O2}}$, respectively, and are configured to provide the fourth and fifth currents I_4 and I_5 to the first and second voltage output nodes $N_{V_{O1}}$ and $N_{V_{O2}}$, respectively.

The first operational amplifier **120** is configured to output a control voltage to the commonly-coupled gates of the PMOS transistors **MP1** to **MP5** to control the first to fifth currents I_1 to I_5 . The first operational amplifier **120** has a non-inverting input coupled to the node N_1 , an inverting input coupled to the node N_2 , and an output coupled to the commonly-coupled gates of the PMOS transistors **MP1** to **MP5**. The first operational amplifier **120** is configured to control the gate voltage of the PMOS transistors **MP1** to **MP5** such that the nodes N_1 and N_2 have the same voltage level. In other words, the nodes N_1 and N_2 are virtually shorted by the operation of the first operational amplifier **120**.

The bipolar transistors **Q1**, **Q2**, and **Q3** operate as first, second, and third pn junction elements, respectively, each of which incorporates a pn junction. As discussed in detail later, the current-voltage characteristics of the pn junctions within the bipolar transistors **Q1**, **Q2**, and **Q3** cause the first to fifth currents I_1 to I_5 to be generated as proportional to absolute temperature (PTAT) currents. In the shown embodiment, NPN transistors are used as the bipolar transistors **Q1**, **Q2**, and **Q3**. The bases of the bipolar transistors **Q1**, **Q2**, and **Q3** are commonly coupled to the collector of the bipolar transistor **Q3**. The collectors of the bipolar transistors **Q1**, **Q2**, and **Q3** are coupled to the nodes N_1 , N_2 , and N_3 , respectively. The emitters of the bipolar transistors **Q1** and **Q3** are coupled to a ground line **180** that provides a low-side power supply voltage V_{SS} , and the emitter of the bipolar transistor **Q2** is coupled to the ground line **180** via the resistor element **R1**. The first, second, and third currents I_1 , I_2 , and I_3 received from the first current mirror **110** flow in the forward directions through the base-emitter pn junctions of the bipolar transistors **Q1**, **Q2** and **Q3**, respectively. In one implementation, the area of the base-emitter junction of the bipolar transistor element **Q3** is the same as that of the base-emitter junction of the bipolar transistor element **Q1**, while the area of the base-emitter junction of the bipolar transistor element **Q2** is N times as large as that of the

base-emitter junction of the bipolar transistor element Q1, where N is a number greater than one.

The second current mirror 130 is configured to provide a sixth current I_6 to the node N_3 , a first neutralization current I_{NL1} to the first voltage output node N_{VO1} , and a second neutralization current I_{NL2} to the second voltage output node N_{VO2} . In the shown embodiment, the second current mirror 130 includes PMOS transistors MP6, MP7, and MP8 that have commonly-coupled gates. The sources of the PMOS transistors MP6, MP7, and MP8 are commonly coupled to the power supply line 170. The drain of the PMOS transistor MP6 is coupled to the node N_3 , and the drains of the PMOS transistors MP7 and MP8 are coupled to the first and second voltage output nodes N_{VO1} and N_{VO2} , respectively. The PMOS transistor MP6 is configured to output the current I_6 from the drains thereof to provide the current I_6 to the node N_3 . The PMOS transistors MP7 and MP8 are configured to output the first and second neutralization currents I_{NL1} and I_{NL2} , respectively, from the drains thereof and to provide the first and second neutralization currents I_{NL1} and I_{NL2} to the first and second voltage output nodes N_{VO1} and N_{VO2} , respectively.

The current levels of the first and second neutralization currents I_{NL1} and I_{NL2} are proportional to the current level of the current I_6 . In one implementation, the current level of the first neutralization current I_{NL1} is A_1 times the current level of the current I_6 , and the current level of the second neutralization current I_{NL2} is A_2 times the current level of the current I_6 , where A_1 and A_2 may be less than one. The current I_6 is used to provide base currents to the bipolar transistors Q1, Q2, and Q3. In one implementation, the current I_6 is the sum current of the base currents to the bipolar transistors Q1, Q2, and Q3.

The second operational amplifier 140 is configured to output a control voltage to the commonly-coupled gates of the PMOS transistors MP6, MP7, and MP8 to control the current I_6 and the first and second neutralization currents I_{NL1} and I_{NL2} . The second operational amplifier 140 has a non-inverting input coupled to the node N_3 , an inverting input coupled to the node N_1 , and an output coupled to the commonly-coupled gates of the PMOS transistors MP6 to MP8. The second operational amplifier 140 is configured to control the gate voltage of the PMOS transistors MP6 to MP8 such that the nodes N_1 and N_3 have the same voltage level. In other words, the nodes N_1 and N_3 are virtually shorted by the operation of the second operational amplifier 140.

The first load component 150 is coupled between the first voltage output node N_{VO1} and the ground line 180. The first load component 150 is configured to generate the first output voltage V_{O1} from the fourth current I_4 received from the first current mirror 110. In the shown embodiment, the first load component 150 includes a diode-connected bipolar transistor Q4 and resistor elements R11 and R12. The diode-connected bipolar transistor Q4 operates as a pn junction element. In one implementation, the base-emitter junction of the bipolar transistor Q4 may have the same area as the base-emitter junctions of the bipolar transistors Q1 and Q3. The bipolar transistor Q4 and the resistor element R11 are coupled in series between the first voltage output node N_{VO1} and the ground line 180. It is noted that the positions of the bipolar transistor Q4 and the resistor element R11 are interchangeable. Further, the resistor element R12 is coupled between the first voltage output node N_{VO1} and the ground line 180 in parallel to the bipolar transistor Q4 and the resistor element R11.

The second load component 160 is coupled between the second voltage output node N_{VO2} and the ground line 180. The second load component 160 is configured to generate the second output voltage V_{O2} from the fifth current I_5 received from the first current mirror 110. In the shown embodiment, the second load component 160 includes a diode-connected bipolar transistor Q5 and resistor elements R21 and R22. The diode-connected bipolar transistor Q5 operates as a pn junction element. In one implementation, the base-emitter junction of the bipolar transistor Q5 may have the same area as the base-emitter junctions of the bipolar transistors Q1 and Q3. The bipolar transistor Q5 and the resistor element R21 are coupled in series between the second voltage output node N_{VO2} and the ground line 180. It is noted that the positions of the bipolar transistor Q5 and the resistor element R21 are interchangeable. Further, the resistor element R22 is coupled between the second voltage output node N_{VO2} and the ground line 180 in parallel to the bipolar transistor Q5 and the resistor element R21.

The voltage-to-current conversion circuit 200 is configured to perform voltage-to-current conversion on the first output voltage V_{O1} to generate the constant output current I_{const} . In the shown embodiment, the voltage-to-current conversion circuit 200 includes an operational amplifier 210, a voltage-to-current conversion resistor Rx, an n-channel metal oxide semiconductor (NMOS) transistor MN11, and a current mirror 220. The operational amplifier 210 has a first input receiving the first output voltage V_{O1} and a second input coupled to a node N_4 . The voltage-to-current conversion resistor Rx is coupled between the node N_4 and the ground line 180. The NMOS transistor MN11 has a gate coupled to the output of the operational amplifier 210, a source coupled to the node N_4 , and a drain coupled to the current mirror 220. The current mirror 220 includes a pair of PMOS transistors MP11 and MP12. The sources of the PMOS transistors MP11 and MP12 are commonly coupled to the power supply line 170 and the gates of the PMOS transistors MP11 and MP12 are commonly coupled to the drain of the PMOS transistor MP11. The current mirror 220 is configured to mirror the current flowing through the voltage-to-current conversion resistor Rx and the NMOS transistor MN11 to generate the constant output current I_{const} .

Although the first load component 150 and the second load component 160 have similar circuit topologies, circuit element parameters of the first load component 150 and the second load component 160 are determined to cause different behaviors between the first output voltage V_{O1} and the second output voltage V_{O2} . One or more circuit element parameters of the first load component 150 (e.g., the resistances of the resistor elements R11 and R12 and the area of the base-emitter junction of the bipolar transistor Q4) are adjusted such that the first output voltage V_{O1} has a non-zero temperature dependence that at least partially cancels the temperature characteristics of the voltage-to-current conversion circuit 200. In some implementations, one or more circuit element parameters of the first load component 150 are adjusted such that the first output voltage V_{O1} has a non-zero temperature dependence that causes the constant output current I_{const} to be substantially constant with temperature. In implementations where the resistance of the voltage-to-current conversion resistor Rx of the voltage-to-current conversion circuit 200 has a significant temperature dependence, the first output voltage V_{O1} may be generated to have a non-zero temperature dependence that at least partially cancels temperature-dependent variations in the output current potentially caused by the temperature-depen-

dent resistance of the voltage-to-current conversion resistor Rx. For example, in implementations where the resistance of the voltage-to-current conversion resistor Rx increases with temperature, one or more circuit element parameters of the first load component 150 are adjusted to increase the first output voltage V_{O1} in accordance with the temperature-dependent increase in the resistance of the voltage-to-current conversion resistor Rx. In contrast, the circuit element parameters of the second load component 160 (e.g., the resistances of the resistor elements R21 and R22 and the area of the base-emitter junction of the bipolar transistor Q5) are adjusted such that the second output voltage V_{O2} is substantially constant with temperature. The second output voltage V_{O2} can be used as a temperature independent reference voltage, similarly to the output voltage of a typical BGR circuit. The following is a detailed description of the operation of the integrated circuit 1000.

In one or more embodiments, the first to fifth currents I₁ to I₅, which are controlled to have the same current level, are each generated as a proportional to absolute temperature (PTAT) current as discussed below. For the base-emitter voltage V_{BE1} of the bipolar transistor Q1 and the base-emitter voltage V_{BE2} of the bipolar transistor Q2, based on the fact that the area of the base-emitter junction of the bipolar transistor Q2 is N times as large as that of the base-emitter junction of the bipolar transistor Q1, the following expressions (1a) and (1b) hold:

$$V_{BE1} = \frac{kT}{q} \ln\left(\frac{I}{I_S}\right), \text{ and} \quad (1a)$$

$$V_{BE2} = \frac{kT}{q} \ln\left(\frac{I}{I_S} \cdot \frac{1}{N}\right), \quad (1b)$$

where I is the current level of the first to fifth currents I₁ to I₅, I_S is the backward saturation current, k is the Boltzmann constant, T is the absolute temperature, and q is the elementary charge.

Since the first and second nodes N₁ and N₂ are virtually shorted and the voltage at the node N₁ is equal to the base-emitter voltage V_{BE1} of the bipolar transistor Q1, the following expression (2) holds:

$$I = \frac{V_{BE1} - V_{BE2}}{R1}. \quad (2)$$

The current level I of the first to fifth currents I₁ to I₅ is represented by the following expression (3), which is obtained by substituting expressions (1a) and (1b) into expression (2):

$$I = \frac{Vt \cdot \ln(N)}{R1}, \quad (3)$$

where V_t is the thermal voltage given by the following expression (4):

$$Vt = \frac{kT}{q}. \quad (4)$$

Expressions (3) and (4) indicate that the current level I of the first to fifth currents I₁ to I₅ is proportional to the absolute

temperature T, i.e., the first to fifth currents I₁ to I₅ are each proportional to absolute temperature (PTAT) current.

The first and second neutralization currents I_{NL1} and I_{NL2}, which are provided to the first voltage output node N_{VO1} and N_{VO2}, respectively, are proportional to the sum of the base currents of the bipolar transistors Q1, Q2, and Q3, but are much smaller than the current level I of the first to fifth currents I₁ to I₅, as discussed below. Due to the operation of the second current mirror 130, the current levels of the first and second neutralization currents I_{NL1} and I_{NL2} are each proportional to the sixth current I₆, which is the sum current of the base currents of the bipolar transistors Q1, Q2, and Q3. Since the base current of an emitter-grounded bipolar transistor is much smaller than the collector current, the sixth current I₆ can be considered to be much smaller than the first, second, and third currents I₁, I₂, and I₃, which are the collector currents of the bipolar transistors Q1, Q2 and Q3. Accordingly, the current levels of the first and second neutralization currents I_{NL1} and I_{NL2} are also much smaller than the current level I of the first to fifth currents I₁ to I₅.

As a first approximation, the effects of the first and second neutralization currents I_{NL1} and I_{NL2} can be ignored (the effects of the first and second neutralization currents I_{NL1} and I_{NL2} are discussed later). In this first approximation, the following expression (5) holds with respect to the first voltage output node N_{VO1}:

$$I = I_{4A} + I_{4B}, \quad (5)$$

where I_{4A} is the current through the resistor element R11 and the bipolar transistor Q4, and I_{4B} is the current through the resistor element R12. With respect to the base-emitter voltage V_{BE4} of the bipolar transistor Q4 and the voltage drops across the resistor elements R11 and R12, the following expression (6) holds:

$$V_{BE4} + I_{4A} \cdot R11 = I_{4B} \cdot R12. \quad (6)$$

From expressions (3) to (6), the current I_{4B} is represented by the following expression (7):

$$I_{4B} = \frac{I \cdot R11 + V_{BE4}}{R11 + R12} = \frac{1}{R11 + R12} \left(\frac{R11 \cdot Vt \cdot \ln(N)}{R1} + V_{BE4} \right). \quad (7)$$

Accordingly, the first output voltage V_{O1} is represented by the following expression (8):

$$V_{O1} = I_{4B} \cdot R12 = \frac{R12}{R11 + R12} \left(\frac{R11 \cdot Vt \cdot \ln(N)}{R1} + V_{BE4} \right). \quad (8)$$

Since the thermal voltage V_t (given by expression (4)) is proportional to the absolute temperature, expression (8) implies that the first order term of the temperature dependence of the first output voltage V_{O1} can be controlled by the resistances of the resistor elements R11 and R1 of the first load component 150. Accordingly, it is possible to cancel the first order term of the temperature dependence of the con-

stant output current I_{const} by appropriately adjusting at least one of the resistances of the resistor elements **R11** and **R1**.

Meanwhile, the second output voltage V_{O2} is represented by the following expression (9), which is obtained similarly to expression (8):

$$V_{O2} = \frac{R22}{R21 + R22} \left(\frac{R21 \cdot Vt \cdot \ln(N)}{R1} + N_{BE5} \right), \quad (9)$$

where V_{BE5} is the base-emitter voltage of the bipolar transistor **Q5**. Expression (9) implies that it is possible to generate the second output voltage V_{O2} to be substantially constant with temperature by appropriately adjusting at least one of the resistances of the resistor elements **R21** and **R22** of the second load component **160**.

The first neutralization current I_{NL1} , which is provided to the first voltage output node N_{VO1} , is used to cancel the second order term of the temperature dependence of the constant output current I_{const} as discussed below. As discussed above, the first neutralization current I_{NL1} is proportional to the sum current of the base currents of the bipolar transistors **Q1**, **Q2**, and **Q3**. Here, the base current I_B of a bipolar transistor can be represented by the following expression (10):

$$I_C = I_B \cdot \beta_F(T), \quad (10)$$

where β_F is the current amplification ratio and I_C is the collector current. As known in the art, the temperature dependence of the current amplification ratio β_F of a bipolar transistor is represented by the following expression (11):

$$\beta_F(T) \propto \exp\left(-\frac{\Delta Eg(N_E)}{kT}\right), \quad (11)$$

where $\Delta Eg(N_E)$ is a constant representing the bandgap narrowing effect in the emitter, which depends on the impurity concentration N_E of the emitter. It is noted that $\Delta Eg(N_E)$ does not depend on the absolute temperature T .

By rewriting expression (11) with a temperature-independent positive constant α defined as $\alpha = \Delta Eg(N_E)/k$, the temperature dependence of the base current I_B for a constant corrector current I_C can be represented by the following expression (12):

$$I_B = \frac{I_C}{\beta_F(T)} \propto \exp\left(\frac{\alpha}{T}\right). \quad (12)$$

By expanding the right side of expression (12) into a Taylor series at a base point $T = T_0$, expression (13) is obtained:

$$\begin{aligned} \exp\left(\frac{\alpha}{T}\right) &\approx \exp\left(\frac{\alpha}{T_0}\right) - \frac{\alpha}{T_0^2} \exp\left(\frac{\alpha}{T_0}\right)(T - T_0) + \\ &\quad \frac{\alpha(2T_0 + \alpha)}{T_0^4} \exp\left(\frac{\alpha}{T_0}\right) \frac{(T - T_0)^2}{2}, \end{aligned} \quad (13)$$

where it holds:

$$\frac{\alpha(2T_0 + \alpha)}{T_0^4} \exp\left(\frac{\alpha}{T_0}\right) > 0. \quad (14)$$

From expressions (13) and (14), it is understood that the base current I_B of a bipolar transistor for a constant current I_C incorporates a second order term of the temperature dependence.

Since the first neutralization current I_{NL1} is proportional to the sum current of the base currents of the bipolar transistors **Q1**, **Q2**, and **Q3**, the first neutralization current I_{NL1} also incorporates a second order term of the temperature dependence. Accordingly, by providing the first neutralization current I_{NL1} to the first voltage node N_{VO1} , it is possible to cause the first output voltage V_{O1} to exhibit a second order term of the temperature dependence. The current level of the first neutralization current I_{NL1} is adjusted based on the temperature dependence of the constant output current I_{const} . By appropriately adjusting the current level of the first neutralization current I_{NL1} , it is possible to cancel the second order term of the temperature dependence of the constant output current I_{const} . In one implementation, the current level of the first neutralization current I_{NL1} may be adjusted with the mirror ratio of the second current mirror **130** with respect to the first neutralization current I_{NL1} , that is, the ratio A_1 of the current level of the first neutralization current I_{NL1} to the current level of the current I_6 .

The second neutralization current I_{NL2} , which is provided to the second voltage output node N_{VO2} , is used to cancel the second order term of the temperature dependence of the second output voltage V_{O2} . Since the above discussion also applies to the second neutralization current I_{NL2} , the second neutralization current I_{NL2} also incorporates a second order term of the temperature dependence. In one implementation, the current level of the second neutralization current I_{NL2} is adjusted to cancel the second order term of the temperature dependence of the second output voltage V_{O2} . In one implementation, the current level of the second neutralization current I_{NL2} may be adjusted by the mirror ratio of the second current mirror **130** with respect to the first neutralization current I_{NL2} , that is, the ratio A_2 of the current level of the second neutralization current I_{NL2} to the current level of the current I_6 .

FIG. 2 shows an example configuration of an integrated circuit **2000**, according to one or more embodiments. In the shown embodiment, the integrated circuit **2000** includes the voltage generator circuit **100** shown in FIG. 1 and further includes a subsequent stage circuit **300** coupled to the first voltage output node V_{O1} and configured to generate an output signal S_{OUT} . In the embodiment shown in FIG. 2, one or more circuit element parameters of the first load component **150** (e.g., the resistances of the resistor elements **R11** and **R12** and the area of the base-emitter junction of the bipolar transistor **Q4**) are adjusted such that the first output voltage V_{O1} has a non-zero temperature dependence that at least partially cancels the temperature dependence of the output signal S_{OUT} . In some implementations, one or more circuit element parameters of the first load component **150** may be adjusted such that the first output voltage V_{O1} has a non-zero temperature dependence that causes one or more characteristics of the output signal S_{OUT} (e.g., voltage, current, frequency, etc.) to be substantially constant with temperature.

FIG. 3 shows an example configuration of the subsequent stage circuit **300** shown in FIG. 2, according to one or more embodiments. In the shown embodiment, the subsequent stage circuit **300** includes the voltage-to-current conversion circuit **200** shown in FIG. 2 and further includes a circuit **400** configured to receive the constant output current I_{const} and generate an output signal S_{out} using the constant output current I_{const} . One or more circuit element parameters of the first load component **150** may be adjusted such that the first output voltage V_{O1} has a non-zero temperature dependence that causes one or more characteristics of the output signal S_{out} (e.g., voltage, current, frequency, etc.) to be substantially constant with temperature. In some implementations, the circuit **400** may be an oscillator circuit configured to generate an oscillating output having a frequency controlled by the constant output current I_{const} . In such implementations, one or more circuit element parameters of the first load component **150** may be adjusted such that the first output voltage V_{O1} has a non-zero temperature dependence that causes the frequency of the oscillating output to be substantially constant with temperature.

FIG. 4 shows an example configuration of an integrated circuit **3000**, according to one or more embodiments. The integrated circuit **3000** includes a voltage generator circuit **3100** instead of the voltage generator circuit **100** shown in FIG. 1. The voltage generator circuit **3100** is configured similarly to the voltage generator circuit **100** shown in FIG. 1 except that the voltage generator circuit **3100** additionally includes a variable resistor element **R2** coupled in series to the resistor element **R1** between the emitter of the bipolar transistor **Q2** and the ground line **180**. It is noted that the positions of the resistor element **R1** and the variable resistor element **R2** are interchangeable. The variable resistor element **R2** has a resistance that is dependent on the power supply voltage **VDD** supplied to the power supply line **170**.

In one or more embodiments, as shown in FIG. 5, an NMOS transistor **MN1** having a gate configured to receive the power supply voltage V_{DD} may be used as the variable resistor element **R2**. The on-resistance of the NMOS transistor **MN1** depends on the power supply voltage V_{DD} , and this property allows the NMOS transistor **MN1** to be used as the variable resistor element **R2**. In this case, the resistance of the variable resistor element **R2** decreases as the power supply voltage V_{DD} increases. In an alternative embodiment, a bias voltage generated from the power supply voltage V_{DD} , for example, through voltage division of the power supply voltage V_{DD} . In other embodiments, a PMOS transistor may be used as the variable resistor element **R4**.

As a first approximation similar to that discussed in the above, the first and second output voltages V_{O1} and V_{O2} generated by the voltage generator circuit **3100** shown in FIG. 4 may be represented by the following expressions (15) and (16), respectively:

$$V_{O1} = \frac{R_{12}}{R_{11} + R_{12}} \left(\frac{R_{11} \cdot V_t \cdot \ln(N)}{R_1 + R_2} + V_{BE4} \right), \text{ and} \quad (15)$$

$$V_{O2} = \frac{R_{22}}{R_{21} + R_{22}} \left(\frac{R_{21} \cdot V_t \cdot \ln(N)}{R_1 + R_2} + V_{BE5} \right). \quad (16)$$

It is noted that expressions (15) and (16) can be obtained by replacing **R1** in expressions (8) and (9) by **R1+R2**. As is understood from expressions (15) and (16), the dependence of the first and second output voltages V_{O1} and V_{O2} on the power supply voltage V_{DD} can be reduced by appropriately selecting the property of the variable resistor element **R2** in

accordance with the dependencies of the output voltages V_{O1} and V_{O2} on the power supply voltage V_{DD} for the case where the variable resistor element **R2** is not used. In implementations where the first and second output voltages V_{O1} and V_{O2} potentially increase as the power supply voltage V_{DD} increases, the dependence of the first and second output voltages V_{O1} and V_{O2} on the power supply voltage V_{DD} can be reduced by using a variable resistor element **R2** configured to have a resistance that increases as the power supply voltage V_{DD} increases. In other embodiments where the first and second output voltages V_{O1} and V_{O2} potentially decrease as the power supply voltage V_{DD} increases, in contrast, the dependence of the first and second output voltages V_{O1} and V_{O2} on the power supply voltage V_{DD} can be reduced by using a variable resistor element **R2** configured to have a resistance that decreases as the power supply voltage V_{DD} increases.

FIG. 6 shows an example configuration of an integrated circuit **4000**, according to one or more embodiments. The integrated circuit **4000** includes a voltage generator circuit **4100** instead of the voltage generator circuit **100** shown in FIG. 1. The voltage generator circuit **4100** is configured similarly to the voltage generator circuit **100** shown in FIG. 1, except that the voltage generator circuit **4100** includes a first load component **4150** instead of the first load component **150** shown in FIG. 1 and a second load component **4160** instead of the second load component **160** shown in FIG. 1.

The first load component **4150** is configured similarly to the first load component **150** shown in FIG. 1, except that the first load component **4150** additionally includes a variable resistor element **R13** coupled in series to the resistor element **R11** and the diode-coupled bipolar transistor **Q4**. The variable resistor element **R13** has a resistance that is dependent on the power supply voltage **VDD** supplied to the power supply line **170**. In one implementation, an NMOS transistor configured to receive the power supply voltage **VDD** at the gate may be used as the variable resistor element **R13**, as discussed in relation to FIG. 5. It should be noted that the positions of the resistor element **R11**, the variable resistor element **R13** and the diode-coupled bipolar transistor **Q4** are interchangeable.

The second load component **4160** is configured similarly to the second load component **160** shown in FIG. 1, except that the second load component **4160** additionally includes a variable resistor element **R23** coupled in series to the resistor element **R21** and the diode-coupled bipolar transistor **Q5**. The variable resistor element **R23** has a resistance that is dependent on the power supply voltage **VDD** supplied to the power supply line **170**. In one implementation, an NMOS transistor configured to receive the power supply voltage **VDD** at the gate may be used as the variable resistor element **R23**, as discussed in relation to FIG. 5. It should be noted that the positions of the resistor element **R21**, the variable resistor element **R23** and the diode-coupled bipolar transistor **Q5** are interchangeable.

As a first approximation, the first and second output voltages V_{O1} and V_{O2} generated by the voltage generator circuit **4100** shown in FIG. 6 may be represented by the following expressions (17) and (18), respectively:

$$V_{O1} = \frac{R_{12}}{R_{11} + R_{12} + R_{13}} \left(\frac{(R_{11} + R_{13}) \cdot V_t \cdot \ln(N)}{R_1} + V_{BE4} \right), \text{ and} \quad (17)$$

$$V_{O2} = \frac{R_{22}}{R_{21} + R_{22} + R_{23}} \left(\frac{(R_{21} + R_{23}) \cdot V_t \cdot \ln(N)}{R_1} + V_{BE5} \right). \quad (18)$$

It is noted that expression (17) can be obtained by replacing **R11** in expression (8) by **R11+R13** and expression (18) can be obtained by replacing **R21** in expression (8) by **R21+R23**. As is understood from expressions (17) and (18), the dependence of the first and second output voltages V_{O1} and V_{O2} on the power supply voltage V_{DD} can be reduced by appropriately selecting the properties of the variable resistor elements **R13** and **R23** in accordance with the dependencies of the output voltages V_{O1} and V_{O2} on the power supply voltage V_{DD} for the case where the variable resistor elements **R13** and **R23** are not used.

FIG. 7 shows an example configuration of an integrated circuit **5000**, according to one or more embodiments. The integrated circuit **5000** includes a voltage generator circuit **5100** instead of the voltage generator circuit **4100** shown in FIG. 6. The voltage generator circuit **5100** is configured similarly to the voltage generator circuit **4100** shown in FIG. 6, except that the voltage generator circuit **5100** additionally includes a variable resistor element **R2** coupled in series to the resistor element **R1** between the emitter of the bipolar transistor **Q2** and the ground line **180**. As discussed in relation to FIG. 5, an NMOS transistor configured to receive the power supply voltage **VDD** at the gate may be used as the variable resistor element **R2**. It should be noted that the positions of the resistor element **R1** and the variable resistor element **R2** are interchangeable.

As a first approximation, the first and second output voltages V_{O1} and V_{O2} generated by the voltage generator circuit **5100** shown in FIG. 7 may be represented by the following expressions (19) and (20), respectively:

$$V_{O1} = \frac{R12}{R11 + R12 + R13} \left(\frac{(R11 + R13) \cdot Vt \cdot \ln(N)}{R1 + R2} + V_{BE4} \right), \text{ and} \quad (19)$$

$$V_{O2} = \frac{R22}{R21 + R22 + R23} \left(\frac{(R21 + R23) \cdot Vt \cdot \ln(N)}{R1 + R2} + V_{BE5} \right). \quad (20)$$

It is noted that expression (19) can be obtained by replacing **R1** in expression (17) by **R1+R2** and expression (20) can be obtained by replacing **R1** in expression (18) by **R1+R2**. As is understood from expressions (19) and (20), the dependence of the first and second output voltages V_{O1} and V_{O2} on the power supply voltage V_{DD} can be reduced by appropriately selecting the properties of the variable resistor elements **R2**, **R13**, and **R23** in accordance with the dependencies of the output voltages V_{O1} and V_{O2} on the power supply voltage V_{DD} for the case where the variable resistor elements **R1**, **R13** and **R23** are not used.

FIG. 8 is a flowchart of an exemplary process **800** for operating an integrated circuit, according to one or more embodiments. The process **800** may be performed by any of the integrated circuits **1000**, **2000**, **3000**, **4000**, and **5000** shown in FIGS. 1 through 7. However, it will be recognized that an input device that includes additional and/or fewer components as shown in FIGS. 1 through 7 may be used to perform the process **800**, that any of the following steps may be performed in any suitable order, and that the process **800** may be performed in any suitable environment.

The process **800** includes providing, by a first current mirror (e.g., the first current mirror **110** shown in FIGS. 1, 2, 4, 6, and 7), a first current (e.g., the first current I_1) to a first node (e.g., the node N_1) coupled to a ground line (e.g., the ground line **180**) via a first pn junction element (e.g., the bipolar transistor **Q1**) at step **802**. The process **800** further includes, providing, by the first current mirror, a second

current (e.g., the second current I_2) to a second node (e.g., the node N_2) virtually shorted to the first node at step **804**. The second node is coupled to the ground line via a second pn junction element (e.g., the bipolar transistor **Q2**) and a first resistor element (e.g., the resistor element **R1**) coupled in series. The process **800** further includes providing, by the first current mirror, a third current (e.g., the fourth current I_4) to a first voltage output node (e.g., the first voltage output node N_{V01}) at step **806**. The process **800** further includes generating, by a first load component (e.g., the first load components **150** and **4150**) coupled between the first voltage output node and the ground line, a first output voltage (e.g., the first output voltage V_{O1}) at the first voltage output node at step **808**. The process **800** further includes generating, by a subsequent stage circuit (e.g., the voltage-to-current conversion circuit **200** shown in FIG. 1 and the subsequent stage circuits shown in FIGS. 2 and 3), an output signal (e.g., the constant output current I_{const} shown in FIG. 1 and the output signal S_{OUT} shown in FIGS. 2 and 3) based on the first output voltage at step **810**. The first output voltage has a non-zero temperature dependence that at least partially cancels a temperature dependence of the output signal of the subsequent stage circuit.

The use of the terms “a” and “an” and “the” and “at least one” and similar referents in the context of describing the invention (especially in the context of the following claims) are to be construed to cover both the singular and the plural, unless otherwise indicated herein or clearly contradicted by context. The use of the term “at least one” followed by a list of one or more items (for example, “at least one of A and B”) is to be construed to mean one item selected from the listed items (A or B) or any combination of two or more of the listed items (A and B), unless otherwise indicated herein or clearly contradicted by context. The terms “comprising,” “having,” “including,” and “containing” are to be construed as open-ended terms (i.e., meaning “including, but not limited to,”) unless otherwise noted. Recitation of ranges of values herein are merely intended to serve as a shorthand method of referring individually to each separate value falling within the range, unless otherwise indicated herein, and each separate value is incorporated into the specification as if it were individually recited herein. All methods described herein can be performed in any suitable order unless otherwise indicated herein or otherwise clearly contradicted by context. The use of any and all examples, or exemplary language (e.g., “such as”) provided herein, is intended merely to better illuminate the invention and does not pose a limitation on the scope of the invention unless otherwise claimed. No language in the specification should be construed as indicating any non-claimed element as essential to the practice of the invention.

Exemplary embodiments are described herein. Variations of those exemplary embodiments may become apparent to those of ordinary skill in the art upon reading the foregoing description. The inventors expect skilled artisans to employ such variations as appropriate, and the inventors intend for the invention to be practiced otherwise than as specifically described herein. Accordingly, this invention includes all modifications and equivalents of the subject matter recited in the claims appended hereto as permitted by applicable law. Moreover, any combination of the above-described elements in all possible variations thereof is encompassed by the invention unless otherwise indicated herein or otherwise clearly contradicted by context.

15

The invention claimed is:

1. An integrated circuit, comprising:
  - a first current mirror configured to:
    - provide a first current to a first node;
    - provide a second current to a second node virtually shorted to the first node; and
    - provide a third current to a first voltage output node;
  - a first pn junction element between the first node and a ground line, wherein the first pn junction element comprises a first bipolar transistor comprising a collector configured to receive the first current and an emitter coupled to the ground line;
  - a first resistor element between the second node and the ground line;
  - a second pn junction element coupled in series to the first resistor element, wherein the second pn junction element comprises a second bipolar transistor comprising a collector configured to receive the second current and an emitter coupled to the ground line via the first resistor element, wherein bases of the first and second bipolar transistors are commonly coupled to each other;
  - a third bipolar transistor comprising a collector coupled to a third node virtually shorted to the first node, wherein the first current mirror is further configured to provide a fifth current to the third node; an emitter coupled to the ground line; and a base coupled to the third node and the commonly coupled bases of the first and second bipolar transistors;
  - a second current mirror configured to provide a sixth current to the third node, and provide a first neutralization current to the first voltage output node;
  - a first load component between the first voltage output node and the ground line, wherein the first load component is configured to generate a first output voltage at the first voltage output node;
  - a second load component between a second voltage output node and the ground line, wherein the first current mirror is further configured to provide a fourth current to the second voltage output node, wherein the second current mirror is further configured to provide a second neutralization current to the second voltage output node, and wherein the second load component is configured to generate a second output voltage at the second voltage output node from the fourth current and the second neutralization current such that the second output voltage is substantially constant with temperature; and
  - a subsequent stage circuit configured to generate an output signal based on the first output voltage, wherein the first load component is configured to cause the first output voltage to increase with an increasing temperature that at least partially cancels a temperature dependence of the output signal of the subsequent stage circuit.
2. The integrated circuit of claim 1, wherein an increase of the first output voltage causes the output signal of the subsequent stage circuit to be substantially constant with temperature.
3. The integrated circuit of claim 1, wherein the subsequent stage circuit comprises a voltage-to-current converter configured to generate an output current as the output signal of the subsequent stage circuit, and wherein an increase of the first output voltage causes the output current to be substantially constant with temperature.

16

4. The integrated circuit of claim 3, wherein the voltage-to-current converter comprises a voltage-to-current conversion resistor used to generate the output current, and wherein the increase of the first output voltage at least partially cancels a temperature-dependent variation in the output current caused by a temperature-dependent resistance of the voltage-to-current conversion resistor.
5. The integrated circuit of claim 1, wherein the first current, the second current, and the third current are each a proportional to absolute temperature (PTAT) current.
6. The integrated circuit of claim 1, wherein the first load component comprises:
  - a second resistor element between the first voltage output node and the ground line;
  - a third pn junction element between the first voltage output node and the ground line; and
  - a third resistor element coupled in series to the third pn junction element.
7. The integrated circuit of claim 6, wherein a resistance of the third resistor element is adjusted based on a temperature dependence of the output signal of the subsequent stage circuit.
8. The integrated circuit of claim 7, wherein the first current mirror is coupled to a power supply line, and wherein the third resistor element comprises a variable resistor element that has a resistance dependent on a power supply voltage supplied to the power supply line.
9. The integrated circuit of claim 1, wherein base currents provided to the first, second, and third bipolar transistors are generated from the sixth current.
10. The integrated circuit of claim 1, wherein a current level of the first neutralization current is adjusted based on the temperature dependence of the output signal of the subsequent stage circuit.
11. The integrated circuit of claim 1, wherein the first current mirror is coupled to a power supply line, and wherein the first resistor element comprises a variable resistor element that has a resistance dependent on a power supply voltage supplied to the power supply line.
12. A method comprising:
  - providing a temperature compensation circuit, wherein the temperature compensation circuit comprises:
    - a first current mirror;
    - a first pn junction element between a first node and a ground line, wherein the first pn junction element comprises a first bipolar transistor comprising a collector and an emitter coupled to the ground line;
    - a first resistor element between a second node and the ground line;
    - a second pn junction element coupled in series to the first resistor element, wherein the second pn junction element comprises a second bipolar transistor comprising a collector and an emitter coupled to the ground line via the first resistor element, and wherein bases of the first and second bipolar transistors are commonly coupled to each other;
    - a third bipolar transistor comprising a collector coupled to a third node virtually shorted to the first node; an emitter coupled to the ground line; and a base coupled to the third node and the commonly coupled bases of the first and second bipolar transistors;
    - a second current mirror;
    - a first load component between a first voltage output node and the ground line;

17

a second load component between a second voltage output node and the ground line; and
 a subsequent stage circuit;
 providing, by the first current mirror, a first current to the first node;
 providing, by the first current mirror, a second current to the second node virtually shorted to the first node;
 providing, by the first current mirror, a third current to the first voltage output node;
 providing, by the first current mirror, a fourth current to the second voltage output node;
 providing, by the first current mirror, a fifth current to the third node;
 generating, by the first load component, a first output voltage at the first voltage output node;
 providing, by the second current mirror, a sixth current to the third node and a first neutralization current to the first voltage output node;
 generating, by the second load component, a second output voltage at the second voltage output node from the fourth current and a second neutralization current such that the second output voltage is substantially constant with temperature; and
 generating, by a subsequent stage circuit, an output signal based on the first output voltage,
 wherein the first output voltage increases with an increasing temperature that at least partially cancels a temperature dependence of the output signal of the subsequent stage circuit.

18

13. The method of claim 12, wherein an increase of the first output voltage causes the output signal of the subsequent stage circuit to be substantially constant with temperature.
 14. The method of claim 12, wherein the output signal is an output current generated by a voltage-to-current converter, and
 wherein an increase of the first output voltage causes the output current to be substantially constant with temperature.
 15. The method of claim 12, wherein the first current, the second current, and the third current are each a proportional to absolute temperature (PTAT) current.
 16. The method of claim 12, wherein the first load component comprises:
 a second resistor element between the first voltage output node and the ground line;
 a third pn junction element between the first voltage output node and the ground line; and
 a third resistor element coupled in series to the third pn junction element.
 17. The method of claim 16, further comprising:
 adjusting a resistance of the third resistor element based on a temperature dependence of the output signal of the subsequent stage circuit.
 18. The method of claim 17, wherein the first current mirror is coupled to a power supply line, and
 wherein the third resistor element comprises a variable resistor element that has a resistance dependent on a power supply voltage supplied to the power supply line.
